UNITED STATES PATENT OFFICE.

FRANK E. MILLER AND GEORGE L. WHEELOCK, OF NEW YORK, N. Y.

SANITARY PROTECTOR FOR WATER-CLOSET SEATS.

SPECIFICATION forming part of Letters Patent No. 634,580, dated October 10, 1899.

Application filed November 14, 1898. Serial No. 696,355. (No model.)

To all whom it may concern:

Be it known that we, FRANK E. MILLER and GEORGE L. WHEELOCK, citizens of the United States, residing in the borough of Manhattan, city of New York, and State of New York, have invented certain new and useful Improvements in Sanitary Protectors for Water-Closet Seats, of which the following is a specification.

10 A frequent cause of disease by transmission from one person to another by infection or contagion is found in the seats of water-closets and privies, whereat persons afflicted with diseases of a private nature—such as venereal 15 diseases, comprising gonorrhea, chancroid, syphilis, and the like—and with diseases such as typhoid and dysentery often leave traces of virus, and if afflicted with vermin leave lice, crabs, &c. Persons fearful of transmission of disease in this manner usually take 20 the precaution to carefully wipe off the seat before using or else tear a hole in a piece of newspaper and apply it to the seat, so that it fits around the hole in the latter. If the paper be torn in the least or if the seat be wet 25 enough to saturate the paper the opportunity for the passage of the germs, &c., to the person using the closet is offered. Furthermore, in view of the possibilities of transmission of 30 disease in the described manner some sanitary method of disinfecting the afflicted part of the body, which is both convenient and desirable, should be resorted to, and even if not wholly efficacious would be welcomed, and 35 hence from a secondary but important point of view the sanitary medium such as forms the subject of the present invention is utilizable.

The object of the present invention is to 40 provide a protecting medium which is anti-septic or germ-proof and which will either kill or prevent the transfer of the germs, if there be any, from the seat to the person using the closet, the protecting medium being con- 45 formed so as to be fitted about the hole in the seat.

The invention consists to these ends of cer- 50 tain new features to be hereinafter described and then particularly claimed.

50 In the accompanying drawings, Figure 1 is a plan view of our protecting medium for closet-seats. Fig. 2 is a plan view showing

our invention applied to a closet-seat. Fig. 3 is a transverse section through the protecting medium on line 33, Fig. 2. Fig. 4 is a plan 55 of a blank from which the protecting medium may be made. Fig. 5 is a plan view of the protecting medium made from such blank applied in proper position to a closet-seat. Fig. 6 is a transverse section through a seat, showing the modified form of protecting medium applied around the hole. Fig. 7 is a plan view of another modification, and Fig. 8 is an enlarged transverse section thereof.

The fabric used for our sanitary closet-seat 65 protector is preferably paraffin paper, which is both antiseptic and waterproof; but other material—such as oiled paper, which is not too thick and which can pass off from the closet-bowl to the sewer without clogging the 70 sewer-pipes—may be used.

Referring to Figs. 1, 2, and 3, B indicates the preferred form of seat-protector, which is of continuous oval or elliptic shape and has a central opening b to correspond with the 75 hole C' in seat C. The front portion b' is made of such size as to extend from the front edge of the hole in the seat over the front edge of the seat itself, so that the front portion of the seat will be fully covered at points liable to 80 be rubbed by the genital organs or region thereof. To avoid objections that might be encountered from the sanitary or plumbing departments of cities, the seat-protecting medium B is made of a plurality of small sec- 85 tions, as shown, which are joined together at a either by a soluble glue or mucilage or they may be connected by compact folds, as shown, which folds will separate more or less easily according to the head of water. Some adhe- 90 sive substance which will dissolve under the action of the water is preferable, however.

As a modification the protecting medium may be formed from a blank of paraffin or other paper, such as A, Fig. 4. The blank A 95 is crimped in such way by a suitable crimping mechanism as to impart a curve thereto and form a protecting medium—such as B', Fig. 5—which is of oval or elliptic shape to conform to that part of the closet-seat C around 100 the hole C'. Due to the crimping along the inner edge b' or in some other way the said edge is turned down, so as to set slightly into the hole C' and hold the main body of the

protecting medium on the seat in proper position around the seat-hole. The protecting medium is so made that the ends may overlap at a' , so that it can be placed around seat-holes of various sizes. This form of the invention can be used to advantage in the country.

A person sitting on a closet-seat provided with the described protecting medium is fully protected against poison virus or germs, as by reason of the imperviousness of paraffin or oiled paper to moisture the germs cannot pass through the paper, and, furthermore, the paraffin is practically antiseptic, as it belongs to the phenol group. The protecting medium is therefore sanitary in its action and is conducive to health by preventing disease and by relieving certain forms of disease through the medication of the body when using the same.

The modified form of the invention shown in Figs. 7 and 8 is cut directly out of paper which is preferably paraffined. The protecting medium d shown is semi-elliptic in shape, with a downturned inner edge d' , and is applied to one end of the seat-hole. A similar piece may be applied to the other end of the seat-hole, so that the same is quite well protected. The direct cutting of the protecting mediums into desired form is not preferred, as there will be waste in cutting, and for that reason we may crimp a straight strip, as A, into proper form; but in producing the form of the invention shown in Figs. 1 to 3 little waste is necessary.

The paper, whether paraffined or not, is also impregnated with some disinfecting or medicating liquid, such as carbolic acid, or some

pleasant-smelling disinfecting liquid, such as thymol, so that the protecting medium is rendered perfectly safe and efficacious. The protecting medium if composed of paraffin-paper need only be paraffined on one side, so that the other side, which should be uppermost, will not adhere to the body, or, instead, the upper surface of the paraffin or equivalent waxy paper may be treated with a thin coat of dry powder, such as prepared chalk or boric acid, which is finely divided, so as to adhere to the surface of the paper and at the same time act as a medicator thereof.

The protecting mediums are made up in suitable packages in any number and then placed on the market.

Having thus described our invention, what we claim as new is—

1. A protecting medium for water-closet seats, &c., the same being of a shape to conform to the hole of the seat, and being composed of sections of suitable fabric which together form a protecting medium, and which are temporarily connected.

2. A protecting medium for water-closet seats, &c., consisting of a sheet of suitable fabric, made up of sections connected by an adhesive substance soluble in water.

In testimony that we claim the foregoing as our invention we have signed our names in presence of two subscribing witnesses.

F. E. MILLER.
GEO. L. WHEELOCK.
